UNITED STATES PATENT OFFICE.

WILLIAM P. KRAUSE, OF CHICAGO, ILLINOIS, ASSIGNOR TO THE AEOLIAN COMPANY,
A CORPORATION OF CONNECTICUT.

PHONOGRAPH AND RADIOADAPTER.

Application filed February 15, 1924. Serial No. 692,988.

To all whom it may concern:

Be it known that I, WILLIAM P. KRAUSE, a citizen of the United States, residing at 4611 Lincoln Avenue, Chicago, Illinois, have invented certain new and useful Improvements in Phonographs and Radioadapters, of which the following is a specification.

My present invention relates to improvements in phonographs and radio adapters by which a radio loud speaker can be readily connected whenever desired directly to the phonograph horn.

In the drawings, Fig. 1 is a vertical fore and aft section, partly in elevation, through the horn-chamber portion of a phonograph equipped with a preferred embodiment of my invention; Fig. 2 is an enlarged portion of Fig. 1 with my loud speaker adapter shown in operative position, said adapter, being partly in vertical section and partly in elevation, and the radio loud speaker being shown in side elevation; Fig. 3 is a plan view of the adapter alone as seen from the right hand side in Fig. 2; and Fig. 4 is an enlarged portion of Fig. 1 to better illustrate the cap or closure.

I will now describe my invention assisted by reference to the specific devices of the drawings.

Fig. 1 shows the horn-chamber portion of a phonograph, 1 being the front of the phonograph cabinet, 2 its back, 3 being the deck separating the tone-arm chamber from the horn-chamber 4 is the phonograph turntable, 5 the sound box, 6 the tone arm and 7 the horn. Said horn may be of any usual construction except that I provide an open-mouthed tubular neck 8 extending from the side of the horn to a hole 9 through preferably the back of the cabinet.

10 is a removable cap for closing both the mouth of the neck 8, as well as the aforesaid hole 9 through the cabinet when it is desired to use the instrument solely as a phonograph and not in connection with a radio set.

For this purpose, the cap shown comprises a circular head of larger diameter than the hole 9, said head being thin and on its underside being substantially flat so as to cover and conceal the hole 9. Said head further has an integral screw-threaded cylindrical stem adapted to engage, as best shown in Fig. 4, the internally screw-threaded mouth of the neck 8.

When it is desired to use the horn of the phonograph with a radio loud speaker, the described cap 10 is unscrewed and removed and is replaced by the loud speaker adapter, as shown in Figs. 2 and 3. This adapter comprises a disk shaped base 11 having a peripheral flange 12. Said base has a central hole through it surrounded by a nipple 13 integral with said base, said nipple being externally threaded to screw into the mouth of the heretofore described tubular neck 8. A U-shaped metal strip 14 is secured by its ends to said peripheral flange 12 and constitutes a yoke for operatively supporting the screw 15, the latter serving to releasably clamp the loud speaker 16 with its mouth against the base 11 of the adapter so as to deliver its sounds through the nipple 13 and the neck 8 into the phonograph horn for amplification. Preferably, a disk 17 of rubber, felt or the like, having a central hole is provided between the base 11 of the adapter and the mouth of the loud speaker so as to give a more effective sound-tight connection.

It will be noted that the yoke 14 is preferably pivotally secured, as shown, to the mouth of the adapter so that said yoke can be swung to one side like a bail after the clamping screw 15 has been retracted, thereby making it easier to remove the radio loud speaker 16, and vice versa, to reinsert it.

The neck 8, while preferably integral, as shown, with the phonograph horn, need not be so but may consist merely of a non-integral tube or the like connected with the horn and extending to the hole provided for the purpose in the wall or other enclosing portion of the phonograph horn-chamber.

It is to be understood that my invention is not to be limited to the specific construction herein shown and described, as it is evident that various other changes might be made in its embodiment without departing from the spirit of the invention or the scope of the appended claims.

What I claim is:

1. In combination with the cabinet-enclosed horn of a phonograph, an open-mouthed tubular neck extending from said horn to a hole in the cabinet; and a removable cap for the mouth of said neck adapted at the same time to act as a closure for said hole in the wall of the cabinet.

2. In combination with the cabinet-en-

closed horn of a phonograph, an open-mouthed tubular neck extending from said horn to a hole in the cabinet; a removable cap for the mouth of said neck; and means ⁶ interchangeable with said cap adapted to operatively support a radio loud speaker at the mouth of said neck; said cap being adapted

to act as a combined closure for the hole in said cabinet and for the mouth of said neck.

In testimony whereof, I have signed my ¹⁰ name to this specification, this 12th day of February, 1924.

WILLIAM P. KRAUSE.
